UNITED STATES PATENT OFFICE.

JULIUS SCHIRRA, OF PITTSBURGH, PENNSYLVANIA, ASSIGNOR, BY DIRECT AND MESNE ASSIGNMENTS, TO PROJECTILE PROTECTOR COMPANY, OF WILMINGTON, DELAWARE, A CORPORATION OF DELAWARE.

PROTECTING-CASING FOR AMMUNITION.

1,288,219.

Specification of Letters Patent. Patented Dec. 17, 1918.

Application filed August 14, 1915. Serial No. 45,548.

To all whom it may concern:

Be it known that I, JULIUS SCHIRRA, a citizen of the United States, and resident of Pittsburgh, in the county of Allegheny and 5 State of Pennsylvania, have invented certain new and useful Improvements in Protecting-Casings for Ammunition, of which the following is a specification.

My invention relates to improvements in 10 protecting casings for ammunition especially adapted for use in the transportation and storage of explosive shells, shrapnel, etc.

For various reasons it is essential that the exterior of explosive shells, shrapnel, and 15 other forms of projectiles, be protected as much as possible prior to their use in actual service. One reason for this is the necessity for protecting the rifling ring of the projectile against damage, the ring being of a 20 character exceedingly susceptible to such action. Another reason is based on possible difficulties in handling, transportation and storage, where the projectile is subject to corrosive effects, rust action, etc.

25 While it is readily possible to provide protective means for this purpose, other correlative conditions arise which limit the possibilities of form, material, etc., of such means, thus eliminating to a large extent the 30 use of the ordinary structures employed for storing and transporting articles of commerce. Among these conditions are the following:

(a) The necessity for using individual 35 structures for each projectile, it being impracticable to pack them in cases without individual protection;

(b) The requirement that the protecting 40 means be sufficiently strong to stand up during the handling, etc., during the life of the projectile and until it reaches the piece of ordnance for firing;

(c) The low cost of manufacture, since the 45 protective means practically becomes waste material when the projectile is finally removed, service conditions not permitting storage, and the relative cost of returning the means to permit its re-use, being excessive.

50 (d) The ability to provide for rapid handling, placing in position and removal.

The present invention is designed to meet these various requirements and conditions in a manner to provide for superior service,

elimination of certain features heretofore 55 considered necessities, and to produce the protective means in the form of a casing which is of simple form, readily manufactured, and of greatly reduced cost.

To these and other ends, the nature of 60 which will be readily understood as the invention is hereinafter disclosed, said invention consists in the improved construction and combination of parts hereinafter fully described, illustrated in the accompanying 65 drawings, and more particularly pointed out in the appended claims.

In the accompanying drawings, in which similar reference characters indicate similar parts in each of the views, — 70

Figure 1 is a plan view of one form of blank which may be employed in the production of my improved casing.

Fig. 2 is a perspective view showing one way in which the casing may be completed. 75

Fig. 3 is a vertical sectional view of the casing shown in Fig. 2.

The casing is formed of suitable material, a preferred material being that commercially known as fiber, this material having the 80 characteristics of strength and toughness, and practically impervious to water, moisture, etc. However, I have employed, with satisfactory results, a material formed by giving a cement coating to the material 85 known as rubber cloth, the coating rendering the material free from absorption and at the same time giving more body to it, tending to stiffen the product, although this stiffness is not equal to that possessed by the 90 fiber material referred to.

The casing is preferably produced from a blank 10, one form of which is shown in Fig. 1, the upper end being slitted to form flaps 10^b, 10^a and 10^c. The blank is also 95 slitted along one edge, as at 10^d, and is provided with openings 10^e for the passage of securing devices. While the blank is shown with its side edges parallel, thus producing a casing of approximately equal diameter 100 throughout its major portion, it will be readily understood that where it is desired to slightly taper the casing toward its upper end, the opposite side edges of the blank may be inclined toward each other to produce this effect, or the upper slit 10^d may have greater length, with the openings 10^e properly positioned. 105

The blank may be produced in any desired manner, as by shearing, through the use of dies, etc., thus enabling them to be formed uniform and with great rapidity.

5 In completing the casing, the blank is rolled into tubular form, the portion of the blank between the slits 10^a slightly raised, as indicated at 11, and the unslotted side edge placed over the slotted edge but under 10 the raised portion 11, thus bringing the side openings 10^a into registration. Suitable securing devices are then passed through these openings to secure the blank in its tubular form, the drawing showing these devices 15 in the form of rivets 12, although other forms of devices may be employed, such, for instance, as would permit ready manipulation to enable the casing to be opened through release of the devices, allowing the 20 blank to be placed in its flattened condition, thereby decreasing objection to storing and transporting the blanks when they become unserviceable for protecting purposes. I 25 preferably employ a cushion over the inner head of the device, as, for instance, the cloth or muslin member 13 which may be cemented to the casing over the head, thereby preventing contact of a metal structure with 30 the surface of the projectile.

30 As will be seen more particularly in Fig. 3, this particular arrangement produces a recess in the interior of the casing, within which recess the head portions of the securing devices remain, thereby maintaining a 35 uniform line in the length of the casing, although the casing is formed with overlapping edges through which securing devices extend, the thickness of the material employed being such as to prevent the formation 40 of recesses or countersunk portions therein sufficient to accommodate the head of the securing device.

The flaps 10^b and 10^c are then brought inward and flaps 10^a brought in overlapping 45 relation with the openings 10^a therein registering, after which securing devices are placed through these openings, completing the casing, the flaps 10^b and 10^c being unsecured and simply extending beneath the 50 bridge formed by the joined flaps 10^a, as indicated in Fig. 3.

As shown more particularly in Fig. 3, the shape of flaps 10^c is such that when the remaining flaps are in position, the side edges 55 overhang in such manner as will permit of being readily gripped to enable the casing to be withdrawn.

The casing is preferably provided with indentations 15, preferably produced while 60 in blank form, these indentations tending to more firmly retain the casing in position on the shell. As these indentations have no sharp edges and are of non-metallic material, they will not damage the surface of 65 the projectile.

As will be readily understood, the construction herein disclosed is not only one of simplicity, but is such as can be manufactured at small cost and a minimum amount of labor. It protects the surface 70 of the projectile and at the same time permits rapid handling without exposing the surface to damage by abrasion. If desired, a fabric may be employed beneath the casing to further decrease such liability, although such use is not essential; or a cement-coated rubber-cloth cap may be employed 75 beneath the casing to insure against corrosion and rust effects. Where the casing is made from fiber, its stiffness will permit 80 close assembling of projectiles in packing, thus enabling the use of simple boxes instead of cellular boxes.

Other advantages will be readily perceived, and while I have shown a preferred 85 form in which the invention may be carried out, it is obvious that changes and modifications may be required or desired to meet the exigencies of use, and I reserve the right to make such changes and modifications 90 for such purpose, in so far as the same may fall within the spirit and scope of the invention as expressed in the accompanying claims.

If desired, the casing may be provided 95 with means which extend across the lower end for preventing endwise movement on the projectile under extreme handling conditions. Such means are obvious, as for instance a cord extending from one side to the 100 other, this being an obvious expedient for the purpose. Under ordinary conditions, such means is not necessary, the substantial fit of the casing and the presence of the indentations serving to retain the casing in 105 position.

Having thus described my invention, what I claim as new is:

1. A protecting casing for ammunition comprising a blank having its side edges 110 joined to form a tube-like member, each side edge having both an overlapping and an overlapped relation to the opposite side edge within the length of the joint, said blank having means extending over a joint end 115 and adapted to act as a support therefor when in protecting position.

2. A protecting casing for ammunition comprising a blank having its side edges joined to form a tube-like member, each side 120 edge having both an overlapping and an overlapped relation to the opposite side edge within the length of the joint, said overlapping arrangement providing an interior recess on the joint line, said blank having 125 means extending over a joint end and adapted to act as a support therefor when in protecting position.

3. A protecting casing for ammunition comprising a blank having its side edges 1

joined to form a tube-like member, each side edge having both an overlapping and an overlapped relation to the opposite side edge within the length of the joint, said overlapping arrangement providing an interior recess on the joint line, and securing means extending through said edges within the recess area, said blank having means extending over a joint end and adapted to act as a support therefor when in protecting position.

4. A protecting casing for ammunition comprising a blank having its side edges joined to form a tube-like member, each side edge having both an overlapping and an overlapped relation to the opposite side edge within the length of the joint, said overlapping arrangement providing an interior recess on the joint line, securing means extending through said edges within the recess area, and means within the recess for preventing contact between the securing means and the projectile.

5. A protecting casing for ammunition comprising a blank having its side edges joined to form a tube-like member, one of said edges extending in substantially a single plane within the joint, the opposite edge extending on parallel planes, whereby an interior recess will be formed in the direction of length of the joint, and securing means extending through the joint within the recess area, said blank having means extending over a joint end and adapted to act as a support therefor when in protecting position.

6. A protecting casing for ammunition comprising a blank having one of its side edges slitted inwardly, the opposite side edge extending into the slits to permit securing the edges together to form a tube-like structure, the edges being in overlapping relation, the portion of the slitted edge between the slits overlapping the unslotted edge to form an interior recess in the direction of length of the slitted edge, said blank having means extending over a joint end and adapted to act as a support therefor when in protecting position.

7. A protecting casing for ammunition comprising a blank having its side edges joined together to form a tube-like structure, said blank having one end slitted to form flaps, the slits being of a length to permit joining of opposing flaps at the end of the structure to form an extended space between the joint and the unslotted portion of the member, said space being adapted to loosely receive the remaining flaps, said side edges having an end extending beneath the joint.

8. A protecting casing for ammunition comprising a blank having its side edges joined to form a tube-like structure, said blank having one end slitted to form flaps, the slits being of a length to permit joining

of opposing flaps at the end of the structure to form an extended space between the flap joint and the unslotted portion of the structure, said space being adapted to loosely receive the remaining flaps, said joined flaps having a width to extend over the loose flaps and form gripping edges to permit manipulation of the casing on the projectile, said side edges having an end extending beneath the joint.

9. A protecting casing for ammunition comprising a blank having one side edge and one end edge slitted inwardly, said slitted side edge being adapted to coöperate with the opposite side edge to form a tube like structure when the edges are in overlapping relation with the slitted edge extending on parallel planes, thereby forming an interior recess within the direction of length of the slitted edge, said slitted end forming flaps at the end of the structure, two of said flaps being adapted to be joined together to form a space to receive the remaining flaps, and securing means for joining the side edges and said pair of flaps in joint relation.

10. A protecting casing for ammunition comprising a tubular structure formed from a blank and having an overlapping joint extending longitudinally of the structure, said structure having an open end and having its opposite end closed by a plurality of flaps, two of said flaps overlapping and being connected together to form a space therebelow to loosely receive the remaining flaps, said flaps acting as a support for the structure and to limit the positioning movements thereof, the joint extending into and forming part of the underlying flap formation.

11. A protecting casing for ammunition comprising a tubular structure formed from a blank and having an overlapping joint extending longitudinally of the structure, said structure having an open end and having its opposite end closed by a plurality of flaps, two of said flaps overlapping and being connected together to form a space therebelow to loosely receive the remaining flaps, said latter flaps extending at approximately right angles to the direction of length of the secured flaps, said flaps acting as a support for the structure and to limit the positioning movements thereof, the joint extending into and forming part of the underlying flap formation.

12. A protecting casing for ammunition comprising a tubular structure formed from a blank and having an overlapping joint extending longitudinally of the structure, said structure having an open end and having its opposite end closed by a plurality of flaps extending in opposed directions and curved in their directions of length, two of said flaps being connected together to form a space therebelow to loosely receive the remaining flaps, said flaps acting as a support

for the structure and to limit the positioning movement thereof, the joint extending into and forming part of the underlying flap formation.

5 13. A protecting casing for ammunition comprising a single blank of commercial fiber having its side edges joined together to form a tube-like structure, and also having one end substantially closed with the 10 closure having opposed recesses permanently open to provide a gripping member

adapted to permit manipulation of the casing relative to the projectile, said joined side edges extending into the closure configuration and underlying said member. 15

In testimony whereof I affix my signature in presence of two witnesses.

JULIUS SCHIRRA.
